APPARATUS FOR DISPENSING OF LIQUIDS

Helge Henric Emanuel Werneman,
Stockholm, SwedenApplication November 26, 1935, Serial No. 51,718
In Sweden November 27, 1934

3 Claims. (Cl. 251—112)

The present invention relates to a device for dispensing liquids. It is of importance in devices of said type that the elements with which the liquid comes into contact may be easily dismounted for cleaning purposes because emulsions and suspensions frequently cause deposits which must be removed to prevent degeneration of the liquid being dispensed. Deposits and degeneration of the suspension or emulsion in the vessel containing it should also be prevented because of the fact that otherwise the liquid does not maintain a uniform composition. In the case of milk and other liquids for drinking purposes it is also important that the liquid be kept and dispensed under such circumstances as to prevent it from taking up foreign matters from the surrounding more or less impure indoor air.

The purpose of the present invention is to provide a dispensing device which fulfills the requirements mentioned above. A further purpose of the invention is to provide improved constructions of a plurality of the elements, as for instance valves, which are used in dispensing the liquid so that these elements will fulfill the general requirements made upon the device as a whole.

A main feature of the invention is that a closed vessel from which the liquid is discharged entirely by the action of pressure generated in the vessel, is connected with a device adapted to enable air or other gas to be supplied under pressure into the vessel for generation of the said pressure, and in connection therewith the invention is further characterized by a device disposed in the closed vessel and by means of which the liquid may be kept or set in motion periodically or continuously, preferably before each discharging operation. By generating pressure in the vessel to discharge the liquid therefrom a very simple and rapid discharging may be obtained, and by combining therewith a stirring device a uniform quality of the dispensed liquid is secured.

Further advantages and features of the invention will be clear from the following description of an embodiment of the invention, reference being had to the accompanying drawings in which

Figure 1 is a vertical sectional view of a building having installed therein an equipment according to the invention.

Figure 2 is a vertical view partly in section and showing on an enlarged scale the dispensing vessel and its outlet pipe according to a modified construction and having a stirring device.

Figure 3 is a horizontal view of a draining cock on an enlarged scale.

Figure 4 is a vertical elevation corresponding to Figure 3 and showing the said cock.

Figure 5 is a horizontal view showing the draining cock with its handle cut away and the plug elevated from its seat to some extent.

Figure 6 is a central sectional view showing a valve for a measuring device in the plant according to Figure 1, and

Figure 7 is an end view of the said valve.

Figure 8 is an elevation of the plug of the cock 10 shown in Figures 6 and 7, taken out of the body of the cock.

Figure 9 is a front view on an enlarged scale, showing a regulating valve for the air pressure conduit shown in Figure 1.

The dispensing plant shown in Figure 1 is intended to be used in sale of milk, and comprises an ordinary milk transport can 1 positioned on the bottom of an ice trough or the like 2. Pressure air may be introduced into the can by way of a conduit 3 which connects the outlet side of a fan 4 with an orifice in the cover 5 closing the can. The fan is driven by an electric or other suitable motor 6. Connected to the inlet side of the fan is a pipe 7 which extends out of the room 25 in which the can is positioned and is provided at its outer end with a filter 8. It is advantageous that the pipe 7 has its outer end in the fresh air and the mouth or the filter on a level over the ground, which is free from dust as much as possible, so that pure fresh air is always supplied to the can. If desired the filter 8 may be disposed at a place other than at the end of the pipe 7 and the end of the pipe 7 may be disposed in a separate chamber other than that in which the can 1 is situated.

With reference to Figure 2, the cover 5 of the can is provided with a centrally projecting socket 9 through which the rotatable outlet pipe is carried. The socket serves partly as a guide for the 40 outlet pipe, and partly as a handle in taking off and putting on the removable cover. The outlet pipe consists of a straight tubular portion 10 extending from the bottom of the can and through and above the socket 9, and a second tubular outlet portion screwed to the first-mentioned tube. The outlet portion of the tube may have various constructions as more particularly described below according as the dispensing device is provided with a measuring device or has a simple draining 50 pipe. A packing formed by a sleeve 11 of rubber or any suitable cellulosic material or the like is provided between the socket 9 and the portion of the tube 10 positioned therein. Said sleeve is clamped to the tube by a screw 12 which is screwed 55

through a holding ring 13 bearing on the top edge of the socket 9. In case the lower end of the tube 10 abuts against the bottom of the can, said end may be cut out as shown at 14 in Figure 2 so as to enable the liquid to enter the tube. The tube 10 is provided with stirring members comprising a helically curved vane 15, which is secured to two studs 16, 17 projecting from the tube. In turning the tube 10 the outside of the 10 packing sleeve 11 slides against the inside of the socket 9, and to reduce the friction the contact surfaces may be covered by any suitable anti-friction means such as paraffin. In case of cellulosic material the packing may be saturated with 15 paraffin.

A clamping arrangement for holding the cover 5 of the distribution vessel is shown in Figures 1 and 2. This arrangement comprises two fork-shaped laps or bosses 29 secured to the cover in 20 diametrically opposite positions. Each lap or boss is intended to accommodate the upper screw threaded portion of a drawing link 30 the lower end of which is formed as a hook 31 which may be attached to one of the handles 32 of the vessel. 25 After the drawing link has been arranged in this manner, the nut 33 screwed to the upper end thereof may be tightened to the upper side of the lap, and the cover 5 together with its packing 34 is clamped in a tight relation to the edge 30 portion 35 of the vessel.

The dispensing device may advantageously be provided with a measuring container for the liquid to be drawn off. A measuring arrangement shown in Figure 1 comprises two measuring 35 vessels 18, 19 superpositioned in a tube 20 which is connected at 21 to the upper end of the tube 10. Each measuring vessel has a definite volume as for instance one sixth of a gallon. A three-way valve 22 is arranged in the lower part of 40 the tube 20, and a lateral outlet pipe 23 extends from the box thereof. A suitable construction of such three-way valve is described with reference to Figures 6-8. Where it is not desired to use the measuring apparatus, any desired quantity of liquid may be drawn off through draining 45 cock 24 arranged in a pipe 25 communicating laterally with the tube 10. Said laterally extending pipe may be fixed to the tube 10 as shown in Figure 1, or it may be removably arranged 50 thereon as shown in Figure 2. The upper one (19) of the measuring vessels is provided at the top thereof with a tubular socket 50, and connected therewith is a vertical conduit 51 which communicates with the free atmosphere, so that 55 fresh air may be sucked into the measuring vessels as the liquid escapes therefrom. A glass bulb 52 or other suitable vessel mounted removably in the conduit 51 serves to accommodate and retard liquid which possibly may, by the 60 action of gas bubbles in the socket 50, be squeezed up above the measuring vessel 19, when it is filled. The pipe between the upper measuring vessel and the glass bulb serves also to take up the excess of liquid from the measuring vessels 65 if these vessels have been filled to a too high level. A filter 53 may be disposed at the outer end of the pipe 51 to prevent dust and other foreign matter from being sucked into the pipe. It is to be noted that the air pressure in the 70 vessel 1 is adjusted by means described below so as always to prevent the liquid level from exceeding under ordinary conditions the level of the socket 50.

The construction according to Figure 2 is 75 adapted to be used in dispensing devices which

do not have a measuring vessel. An elbow pipe 25' is screwed to the threaded top end of the tube 10, and the draining cock 24 is provided at the end of the lateral branch thereof. Extending from the bottom of the cock body is a 5 socket 26, the threaded lower end of which has an outlet mouth 27 screwed thereto. A handle knob 28 is secured to the top of the cock body.

An embodiment of the draining cock 24 is shown in detail in Figures 3-5. The cock, like 10 the other elements of the plant, is constructed so as to permit an easy dismounting for cleaning purposes, which is very important from a hygienic point of view. According to the invention the plug of the cock may be removed by a simple 15 manipulation to be cleaned and may afterwards be replaced in an entirely tight position with the same facility. To this end the small end of the conical plug 37 has a stud 38 from which a pin 39 projects on right angles. One end of a 20 leaf spring 41 is secured to pipe 25 and the other end is adapted to yield longitudinally to the plug 37 and comprises a slot 42 corresponding to the stud 38 and its pin 39 so that both of said elements may be carried through the slot after the 25 plug has been turned to the angular position shown in dotted lines in Fig. 4. Adjacent to its large end the plug is provided with a projecting pin 45, and when the plug is completely introduced in the body of the cock, said pin 45 engages 30 a recess 44 made in the surrounding edge of the body and forming therein two shoulders 43 for the pin 45. The pin 39 of the stud 38 forms an angle with the slot 42 as long as the pin 45 engages the recess 44 and its movement is limited 35 by the shoulders 43, and in consequence the cock is prevented from being removed. The cock is kept in said tight position by the spring due to the tensioning action thereof on the plug in its longitudinal direction. In case it is desired to remove the plug, the small end of the stud 38 is 40 acted upon so as to displace the plug against the action of the spring 41 to an extent sufficient to elevate the pin 45 out of the recess 44 and on a level beyond the outer edge of the cock body as 45 shown in Figure 5, whereupon the cock may be turned freely so that the pin 39 will register with the slot 42 and the plug may be removed from the body 40.

The three-way valve or cock controlling the 50 supply of liquid to the measuring vessels and the discharge thereof may be constructed as shown in detail in Figures 6-8. The valve body 55 has a socket 56 to be connected to the ascending pipe 10 from the vessel 1, and a socket 57 55 in which the connecting pipe of the measuring vessels is adapted to be secured. The plug 58 has formed in its conical seat two recesses or channels 59 and 60 forming the passages of the cock. A particular advantage is that said 60 passages are formed as recesses in the seating surface instead of being holes through the plug because the cleaning of the plug may be facilitated on account thereof. The recess 59 extends peripherally and establishes communication between the socket 57 and the outlet pipe 23 on the valve body. The recess 60 has besides a peripheral portion also a portion 61 extending longitudinally to the plug, because the sockets 57 and 62 communicating with each other by way of said 65 recess are positioned in separate planes of the plug. At its large end the plug has a handle 62 which is bored to receive a push stem 63 comprising a push knob 64 which may be pressed inwards against the action of a spring 65. An 70 75

abutment pin 66 is secured on the push stem and extends through a longitudinal slot 67 in the handle. The spring tends to keep the stem and its pin 66 in an upper terminal position in which 5 the pin 66 engages the upper end of the slot 67; on the other hand the push stem may be pressed in by operating the knob 64 so as to force the pin to its second terminal position in engagement with the lower end of the slot. The latter position 10 is shown in Figure 6 in which the spring 65 is thus compressed. On the outside of the valve body 55 there are two projections 68 and 69. Said projections are so formed that when the handle 62 is set at for instance the position shown 15 in dotted lines in Figure 7, the pin 66 impinges and is stopped by one of the projections (68), in case the pin occupies its lower terminal position. The pin 66 impinges and is stopped by the other projection 69 when it is in its upper 20 terminal position. The projection 69 comprises a laterally projecting abutment 70 positioned in that path of the pin 66 in which said pin travels in its upper position. In order that the handle may be moved past the projection 69 after it has 25 passed the projection 68, the pin must be forced downwards so as to pass below the abutment 70. No communication is established between any of the sockets 56, 57, and 23 when the handle is set so as to have the pin 66 in engagement with 30 the abutment 70. On the other hand, when the handle is turned to the right in Figure 7, so that an abutment pin 71 secured to the plug of the cock impinges a shoulder 72 in the body 55, a communication is established between the socket 35 56 and the socket 57 by way of the angular recess 60 of the plug of the cock. Finally, when the handle is turned to the left to the position illustrated in dotted lines in Fig. 7 and in which the abutment pin 71 engages, a shoulder 73 in 40 the body of the cock, there is an open communication between the socket 57 and the draining socket 23 by way of the recess 59. The stopping device formed by the stop pin 66 and the projections 68 and 69 is intended to indicate the closing 45 position of the cock and to prevent the cock from being set too rapidly from one terminal position to the other position which could cause an inadequate measurement.

The fan generating the pressure in the vessel 1 50 is intended to deliver a constant outlet pressure. In order to enable a certain regulation of the air pressure in the pipe 3 and the vessel 1 connected therewith, a valve 75 may be provided at the pressure side of the fan as shown in Figure 1, 55 through which valve a variable part of the pressure air may be discharged so as to decrease the pressure to any extent desired. In addition to this regulating valve 75 a cock 76 shown on an enlarged scale in Figure 9 is disposed in the pipe 60 3. Said cock may be set in two positions only, and in both of said positions there is always a communication between the fan and the vessel 1, but in one of them there is also a communication open to the free atmosphere by a discharge pipe 77 so that a predetermined part of the pressure air may escape in said position. When the vessel 1 is filled completely and, 65 consequently, a relatively small pressure is required to force the liquid into the measuring vessels, the cock 76 is set in a position in which said communication is open, but when the vessel 1 is half emptied, the cock 76 is set in a position in which the said communication is shut off and the 70 entire air pressure is applied to the vessel by 75

way of the cock. The pressure is in this case determined by the valve 75.

The motor 6 driving the fan may be operating continuously or intermittently, i. e. be started at each discharging operation in the vessel 1. 5 A switch 78 for starting and stopping purposes may be positioned adjacent to the vessel 1 and an indicating lamp 79 may be coupled to the circuit of the motor so that it is lighted when the motor is in motion. 10

In drawing off and measuring a desired quantity of liquid such as milk the liquid in the vessel 1 is first stirred by oscillating the tube 10 by means of the handle 28, thereupon the fan is started. Then the valve 22 is set in the position 15 in which the ascending pipe 10 communicates with the measuring vessels 18 and 19 so that the air pressure generated by the fan and transmitted by the pipe 3 to the vessel 1 forces the liquid up into the measuring vessels 18, 19. When 20 these vessels have been filled to a desired level, the communication with the vessel 1 is shut off whereupon the valve 22 is set so as to open the communication with the draining socket 23 and to allow the liquid to escape from the measuring 25 vessels.

The use of a fan driven by an electric motor as a pressure generating means causes special advantages because such a propelling means neither in its stopped nor its working condition 30 shuts off the connection between the inlet and the outlet pipe thereof so that the vessel 1 connected to these pipes always communicates with the free atmosphere. The vessel 1 is therefore at any moment ventilated, and the liquid must not be 35 affected by pressure air in a closed vessel, when no draining or measuring is going on. Furthermore, when the fan is stopped, a momentary reversion of the air from the pressure side of the fan to the suction side thereof occurs, and a blast 40 of air is transmitted back to the filter 8 at the mouth so that dust and the like which could have adhered to the filter during the suction period is blown away. An automatic cleaning of 45 the filter is thus obtained. The driving motor and the fan may be started rapidly and deliver almost instantly the pressure needed whereby the dispensing may take place directly after starting. 50

Though I prefer a fan as the pressure generating means in the plant according to the invention, it is possible to use a manually operable plunger pump for this purpose. A motor driven plunger compressor or a pressure gas container having a pressure reducing valve may also be employed. 55

It will be understood that numerous modifications may be effected without departing from the spirit of the invention or exceeding the scope of the following claims.

I claim:—

1. A cock comprising a body member and a removable tapering plug, a spring secured to said body member and to one end of said plug and tensioned to force said plug onto its seat in said body member, and means for locking the spring to the plug as long as the rotational motion thereof is limited within a predetermined angular range. 60

2. A cock comprising a body member and a removable tapering plug, a spring secured to said body member and to one end of the plug and tensioned to force said plug onto its seat in said body member, and a bayonet joint serving to lock the spring to the plug within a predetermined range of angular movement of the plug and to permit the separation of the plug and spring at 70 75

an angular position of the plug beyond said range.

3. A cock comprising a body member and a removable tapering plug, a spring secured to said body member and to one end of the plug and tensioned to force said plug onto its seat in said body member, a projection secured to the large end of said plug, shoulders arranged in said body member adapted to cooperate with said projection to limit the range of rotational movement of

the plug while the latter is in its seated position, a bayonet joint adapted to lock the spring to the plug while the latter is within said limited range of rotational movement and to be released by displacing the plug longitudinally so as to permit said projection to pass said shoulders and rotating the plug beyond said limit. 5

HELGE HENRIC EMANUEL WERNEMAN.
